F. G. HALL

MORTAR FOR THROWING LINE CARRYING PROJECTILES

Filed Oct. 27, 1920

UNITED STATES PATENT OFFICE.

FRANK G. HALL, OF PHILADELPHIA, PENNSYLVANIA.

MORTAR FOR THROWING LINE-CARRYING PROJECTILES.

Application filed October 27, 1920. Serial No. 419,923.

To all whom it may concern:

Be it known that I, FRANK G. HALL, a citizen of the United States, and residing at Philadelphia, Philadelphia County, State of Pennsylvania, have invented certain new and useful Improvements in Mortars for Throw-
ing Line-Carrying Projectiles, of which the following is a specification.

This invention relates to mortars and par-
ticularly to mortars designed and construct-
ed to throw line carrying projectiles. Many
forms of guns and mortars for throwing
line carrying projectiles have heretofore
been designed or suggested for throwing
lines from vessel to vessel at sea or between
the shore and a vessel for establishing com-
munication for the purpose of saving lives,
salvage, towing, etc. The present invention
is an improvement on prior devices of this
kind and provides a mortar which is simple,
light and strong, and which may be quickly
“knocked down” for transportation from
place to place.

The mortar has three principal parts, the
base, the carriage, and the barrel, other parts
being provided to secure the carriage and
the barrel together, the arrangement being
such that these securing parts may be easily
and quickly manipulated so that the barrel
and carriage may be conveniently separated
for the purpose of transportation, and the
carriage and base being also readily separ-
able, for the same reason.

An important feature of the invention re-
sides in the manner in which the barrel is
connected to the carriage. Instead of the
usual trunnions heretofore provided midway
of the barrel in mortars of this type, the
breech end of the barrel is mounted on an
axle supported in the carriage and is free
to swing about this axle as a pivot. The
axle is located substantially in the middle
of the carriage and the force of recoil is ex-
erted along a line which passes through the
carriage close to the pivotal axis of the bar-
rel. This construction largely eliminates the
“jump” of the piece in firing which, in some
types of mortars, is sufficient to throw the
piece over backwardly. The accuracy of
the piece is naturally increased by this con-
struction. It has heretofore been difficult to
attain the necessary accuracy in firing mor-
tors of this type, inasmuch as the projectile
is always relatively heavy as compared with
the weight of the mortar, the powder charge

large, and the reaction or recoil force exces-
sive.

As line throwing guns must frequently be
used by vessels at sea and must therefore be
lashed to the deck, and as a vessel afloat con-
stantly changes its direction, it is desirable
to so mount the gun that it may be lashed
but yet so that it may be traversed to follow
a moving target. A novel form of base is
provided therefore upon which the carriage
is pivotally mounted, the base being adapted
to be lashed to a deck or framework of the
vessel, the carriage having a limited swing-
ing movement relatively to the base, and
means being provided for locking the car-
riage and base together in the desired angu-
lar relationship.

A further object of the invention is to pro-
vide a mortar which is compact, enabling it
to be installed in small space, which is of
great importance when the gun is to be car-
ried on vessels such as tug boats, etc. Fur-
ther objects are; to provide a mortar of this
class in which the adjustment for elevation
of the barrel may be quickly and easily ac-
complished; and in which means is provided
for preventing the water, which normally
flows down outside of the barrel in wet
weather, from entering the interior of the
powder chamber through the priming open-
ing to wet the powder or other explosive
therein. Other objects and advantages of
the invention will be apparent as it is dis-
closed in the following description when
taken in connection with the accompanying
drawings in which:

Figure 1 is a side elevation of the mortar;

Figure 2 is a top view of the same;

Figure 3 is a section on line 3—3 of Fig-
ure 1; and

Figure 4 is a rear view of the mortar.

The mortar comprises essentially a base 9,
a carriage 10 positioned on the base, and a
barrel 11 mounted on the carriage and, while
these parts are preferably cast, they may be
fabricated in any well known manner. The
base 9 has a pin 9' extending upwardly
therefrom at one end and the opposite end
of the base, which is considerably wider, has
a plurality of circular apertures 9² therein
which are disposed along an arc having its
center in the axis of the pin 9'. Forwardly
extending flanges 9³ are provided at the
front corners of the base and each of these
flanges has an aperture 9⁴ therein through

which ropes may be passed for the purpose of lashing the base to the deck of a vessel or to some other suitable stationary object.

The carriage 10 has two parallel bottom plates 10' held in spaced relation by cross pieces 10² integral therewith, the rear cross piece having a boss provided with a cylindrical aperture to receive the pin 9' on the base. Each plate is also perforated at its forward end as at 10⁸, these perforations being so positioned that they may be brought into register simultaneously with two of the apertures 9² in the base. To lock the forward end of the carriage to the base removable pins 14 are provided which are adapted to extend through the registering openings 10⁸ and 9² in the carriage and base respectively. These pins prevent accidental swinging of the carriage relatively to the base around the pin 9', but may be removed to allow the carriage to be traversed, after which they may again be inserted to hold the carriage in its new relative angular position. Each of the bottom plates of the carriage has, along its inner edge, a vertically extending flange portion, the height of which varies from front to rear. A portion of each of these flanges, approximately midway of the base, is thickened as indicated at 10³, and these thickened portions are provided with aligned cylindrical apertures or bearings 10⁴. At the front and rear the vertical flanges are cut away as at 10⁵ and 10⁶ whereby handles are formed by which the carriage may be conveniently grasped and lifted. Near the front of the carriage and immediately in rear of the handles the vertical flanges are extended upwardly to form spaced parallel pedestals which are preferably arc-shaped, the centers of the arcs lying on the axis of aligned apertures 10⁴. These arc-shaped pedestals are provided with series of aligned apertures 10⁷.

The barrel 11 of the mortar has, extending rearwardly from its breech end, two spaced flanges 11' which are provided with aligned apertures of the same size as the apertures 10⁴ of the carriage. At a point intermediate the ends of the barrel it is provided with two parallel and downwardly extending projections or flanges 11² provided with aligned apertures 11³ therein of the same size as apertures 10⁷.

In assembling the barrel and carriage the axle or shaft 12 is extended through the apertures 10⁴ of the carriage and the apertures in the flanges 11' of the barrel, and a member 13 is inserted through aligned apertures

10⁷ and 11³ of the carriage and barrel respectively and the barrel will be thereby maintained in fixed position on the carriage as long as both of the members 12 and 13 remain in position. Suitable cotter pins 12' and 13' respectively are provided to prevent the accidental displacement of either of these members. The barrel can of course pivot about the axle 12 and when it is desired to adjust the same for elevation the pin 13 is removed, the barrel elevated or depressed and the pin reinserted in the apertures 10⁷ selected.

It is often the case that the mortar is employed in wet weather and that rain, flying spray, etc., will wet the barrel and will run down in streams along the same. To prevent a flow of water into the powder chamber through the priming opening I have provided a lug 11⁴ on the barrel through which the priming opening is formed and it will be obvious that water flowing down the length of the barrel cannot find its way through the priming opening and into the powder chamber. The barrel is of light construction and to strengthen the same, especially against the effects of rough handling when detached from its base, strengthening ribs 11⁵ are provided, which extend from the thickened breech end portion convergingly towards the muzzle. Although four of these ribs are illustrated others may be provided, if found necessary or desirable.

It will be obvious that changes may be made in the design and arrangement of parts of the invention which is therefore not limited in its scope to the exact embodiment disclosed.

Having thus described the invention what I claim as new and desire to secure by Letters Patent is:

In a mortar of the class described, in combination, a portable base adapted to be secured to a deck or other stationary object and having a pin projecting upwardly therefrom and also having a plurality of apertures therein disposed along an arc having said pin as a center, a carriage having an aperture at its rear end to receive said pin and having an aperture at its front end adapted to be brought into register with any one of said apertures in the base, removable means for inserting into two such aligned apertures to prevent relative movement of the carriage and base, and a barrel mounted on said carriage.

In testimony whereof I affix my signature.
FRANK G. HALL.
